UNITED STATES PATENT OFFICE

19,288

METHOD OF TREATING FIBROUS MATERIALS

Thomas W. Bacchus, Wilmington, Del., assignor to Hercules Powder Company, Wilmington, Del., a corporation of Delaware

Original No. 1,856,453, dated May 3, 1932, Serial No. 483,835, September 23, 1930. Application for reissue May 22, 1934, Serial No. 727,000

9 Claims. (Cl. 92—7)

My invention relates to a method for treating fibrous materials, as for example, cotton linters, straw, wood, or the like.

In the preparation of fibrous materials for various purposes, it is desired to effect removal from the materials of hull particles or lignous impurities, to effect saponification of the oils and emulsification of the waxes, etc., and for certain purposes, as in the preparation of cellulose materials for nitration, it is desirable to effect reduction in the viscosity of such materials. Heretofore in the treatment of fibrous materials, it has been generally customary to place the materials in large kiers or digesters together with an aqueous caustic soda solution of suitable concentration, or with sulphate liquor, or other purifying solution, and the contents heated, either directly or indirectly, under a pressure between about atmospheric and 150 pounds, depending upon the result desired to be obtained. The treatment in the kiers or digesters has heretofore been continued for from 1 to 18 hours or more. At the end of the period of treatment the pressure is released from the kiers or digesters, the liquor drained from the material and the material washed, bleached, dried, etc. as desired.

As an example of the treatment of fibrous materials by methods heretofore known, dry cotton linters are placed in a kier or digester with, for example, a 1%—4% sodium hydroxide solution in, for example, the ratio of 6 parts of sodium hydroxide solution to 1 part cotton linters. Steam is applied to the kier or digester at a pressure of, for example, 60 pounds and maintained for a period of, for example, 5 hours, after which the pressure is released, the liquor drained off and the treated linters washed with water, subjected to treatment with a suitable bleaching agent and finally dried.

The method heretofore used in the treatment of fibrous materials, as above briefly outlined, is disadvantageous for many reasons, chief among which are that it involves batch operation, requires large and expensive apparatus, which in operation presents various problems of control, is expensive to maintain, and, at the same time, is capable of only a limited output.

Now, in accordance with my invention, I have discovered that the desired treatment for the purification of fibrous materials and desired reduction in viscosity may be effected in a continuous manner by continuously passing the material to be treated in admixture with a desired solution for effecting the treatment, through a

zone wherein the fibrous material is subjected to the action of heat and pressure, the discharge from such a zone being controlled.

In the practical adaptation of the method in accordance with my invention, for example, the fibrous material, as cotton linters, straw, comminuted wood, or the like, to be purified, in admixture with a purifying solution may be pumped through a passage, the discharge from which is controlled and in which the mixture of fibrous material and purifying solution is subjected to heat at the desired temperature and maintained under the desired pressure. The temperature will desirably be substantially above the boiling point of the treating solution, i. e. substantially above, and preferably will be above about 140° C.

As a more specific illustration of the practical adaptation of my invention, cotton linters, straw, comminuted wood or the like, may be mixed in a suitable container with a purifying solution, such as a solution of sodium hydroxide, sulphate liquor solution, etc. The mixture may be pumped from the container through a coil of tubing, the outlet from which is suitably controlled as, for example, by providing a suitable valve, connecting with a standpipe, or otherwise providing for control of the outlet.

Having now indicated in a general way the nature and purpose of my invention, I will more specifically describe a preferred practical adaptation thereof by way of illustration in connection with, for example, the purification of cotton linters and with reference to the accompanying drawing by which is illustrated diagrammatically a form of apparatus adaptable for the carrying out of the method embodying my invention.

Referring to the drawing, A indicates a container desirably fitted with some form of agitating device in which the material to be treated may be mixed with a treating solution. B indicates a pump, the suction side of which is connected with the container A and the discharge side of which is connected to the inlet end of a coil of pipe C. A portion of the coil of pipe C adjacent to the discharge of the pump B is jacketed as shown at d, the jackets being connected and provided with an inlet and discharge for steam. The coil adjacent its discharge end is jacketed as shown at e, the jackets being connected and provided with an inlet and discharge for cooling water. The portion of the coil intermediate the jackets d, e, is covered with insulating material, as for example, asbestos, or the like, as indicated at G.

The discharge or outlet end of the coil C is con-

5 nected to a valve casing *H*, within which is pro-
vided a valve seat on which is adapted to seat
a conoidal shaped valve *i* provided with a stem *k*
extending through a stuffing box *l* in the casing,
and provided at its outer end with a head *m*
against which abuts one end of a spring *n*, the
other end of which abuts against an adjustable
stop *o* carried by a bracket *p* attached to the
casing. The valve casing *H* is desirably connect-
10 ed to a standpipe *Q*, which extends upward for
a substantial distance and returns to connection
with a surge tank or receiving tank *R* from which
a discharge *S* is provided. Adjacent the upper
portion of the stand pipe *Q* a vent *t*, provided with
15 a suitable valve *u*, is provided. If desired the
standpipe *Q* may be omitted and the valve casing
connected directly to the surge tank *R*, or the
valve *i* may be omitted and the coil *C* connected
directly to standpipe *Q*.
20 Connected to the discharge or outlet end of the
coil *C*, or connected to the coil adjacent the dis-
charge or outlet end, is a pipe *V* provided with
a suitable valve *w*. Pipe *V* is connected to the
discharge side of a pump *X*, the inlet side,
25 through a pipe *Y*, being connected with a suitable
source of purifying solution or of water.

30 In carrying out the method in accordance with
my invention, in the apparatus above described,
for example, cotton linters are placed in the con-
tainer *A* together with an aqueous caustic soda
solution of .5%-2% strength, in the proportion of
35 say 1 part of cotton linters to 50 parts of caustic
soda solution by weight. The mixture of cotton
linters and caustic liquor is then pumped by the
pump *B* through the coil *C* at a velocity of say
about 2 feet per second. The mixture of cotton
40 linters and caustic solution are brought to a suit-
able temperature, say about 165° C. by the in-
troduction of steam into the jackets *d* or, if
desired, live steam may be injected into the coil
at a suitable point or points to obtain the desired
45 temperature. The temperature of the mixture
of cotton linters and caustic solution is main-
tained at approximately 165° C. in its travel
through that part of the coil which is insulated,
and is suitably reduced to a point below the boil-
50 ing point of the caustic solution before discharge
from the coil through the introduction of cool-
ing water into the jackets *e*. The mixture is de-
sirably maintained under a pressure of about 200
lbs. per square inch in its passage through the
55 coil, by adjustment of valve *i*.

55 In the treatment of cotton linters as indicated
above, the section of the coil provided with steam
jackets *d* may be of any suitable length to obtain
the desired temperature and the portion of coil
provided with cooling jackets *e* may be of any
60 desired length to obtain the desired cooling. The
insulated section of the coil in which the desired
temperature is maintained will desirably be about
three thousand feed long.

65 Discharge of the mixture of cotton linters and
caustic solution from the coil *C* is controlled by
the valve *i*, which, it will be noted, is so mounted
that should cotton jam in the valve and tend to
back up in the coil, the valve *i* may open and re-
lieve any jam. Thus, the valve will tend to uni-
70 formly control discharge from and hence equalize
the pressure on the coil *C*. The mixture of cotton
linters and caustic solution discharged from the
coil *C* will, after passing through the valve, pass
up standpipe *Q* and down into tank *R*. The
standpipe *Q* may be made of any desired height,
its purpose being primarily to cooperate with the
75 valve *i* in controlling the discharge from and

80 equalize the pressure on the coil *C*. Under cer-
tain circumstances the control of the discharge
from the coil *C* may be effected by connecting the
discharge directly with the standpipe *Q*, the valve
85 *i* being omitted. In such case the standpipe *Q*
would be made of sufficient height so that de-
sired control of the discharge from the coil would
be effected through the pressure of the column of
90 cotton linters and solution in the standpipe. It
will be noted that the standpipe is provided with
a vent controlled by a suitable valve in order to
prevent or control the creation of a vacuum by
the downwardly passing cotton linters and solu-
95 tion upon the column communicating with the
coil.

100 During the passage of cotton linters and solu-
tion through the coil *C* spent caustic soda solu-
tion or water is desirably pumped by pump *X*
through the pipe *V* and passes with the cotton
105 linters and solution discharged from the coil
through the valve *i*. The spent caustic soda solu-
tion or water supplied by pump *X* acts to increase
the ratio of caustic soda solution to cotton over
that of the mixture discharged from the coil with
the result that the mixture will more readily pass
110 through the valve *i*.

115 The cotton linters discharged into tank *R* may
be drawn therefrom as desired for separation
from the purifying solution, washing and sub-
jecting to such other treatment as may be de-
sired.

120 The product withdrawn from tank *R*, as for
example, cotton linters, straw, comminuted wood,
or the like, which may have been treated, will be
found to have great purity, to be free from waxes,
oils and from hulls and encrusting materials and
125 to be of a desired reduced viscosity. The product
will be obtained with great reduction of time,
labor, and with very simple apparatus.

130 It will be appreciated that in the carrying out
of my invention the precise temperature and
pressure used and the time of treatment will de-
pend upon the material treated and the desired
characteristics of purity, reduced viscosity, soft-
ness, etc. desired. It will be appreciated that the
135 time of treatment may be readily varied for the
treatment of any particular material and for the
production of any particular grade of product by
a regulation of the velocity at which the material
is passed through the zone of treatment or coil
and the extent of the zone or coil.

140 It will be appreciated that the method in ac-
cordance with my invention is not dependent upon
the use of any particular form of apparatus and
that that described herein is disclosed merely for
purposes of illustration. It will be further ap-
preciated that in carrying out the method in ac-
cordance with my invention various modifications
145 may be made without departing from my inven-
tion.

150 What I claim and desire to protect by Letters
Patent is:

1. The method of treating fibrous material
which includes forcing a mixture of fibrous ma-
terial and a treating solution under pressure
through a passage, heating the mixture adjacent
the inlet end of said passage, cooling the mixture
adjacent the discharge end of said passage and
controlling the discharge from said passage. 140

145 2. The method of treating cotton linters which
includes forcing a mixture of cotton linters and a
caustic soda solution under pressure through a
passage, heating the mixture at a point within
said passage, cooling the mixture adjacent the 150

- discharge end of said passage and controlling the discharge from said passage.
3. The method of treating fibrous cellulosic material which includes forcing a mixture of fibrous cellulosic material and an alkaline treating solution through a passage, heating the mixture within the passage to a temperature substantially above the boiling point of the treating solution at atmospheric pressure, cooling the mixture adjacent the discharge end of said passage to a temperature below the boiling point of the treating solution and controlling the discharge from said passage. 80
4. The method of treating fibrous cellulosic material which includes forcing a mixture of fibrous cellulosic material and an alkaline treating solution comprising an aqueous solution of caustic soda, through a passage, heating the mixture within the passage to a temperature higher than about 140° C., cooling the mixture adjacent the discharge end of said passage to a temperature below the boiling point at atmospheric pressure of the treating solution and controlling the discharge from said passage. 90
5. The method of treating cotton linters which includes forcing a mixture of cotton linters and a treating solution comprising an aqueous solution of caustic soda, through a passage, heating the mixture within the passage to a temperature substantially above the boiling point of the treating solution at atmospheric pressure, cooling the mixture adjacent the discharge end of said passage to a temperature below the boiling point of the treating solution and controlling the discharge from said passage. 100
6. The method of treating cotton linters which includes forcing a mixture of cotton linters and a treating solution comprising an aqueous solution containing about 0.5-2% sodium hydroxide by weight, through a passage, heating the mixture within the passage to a temperature substantially above the boiling point of the treating solution at atmospheric pressure, cooling the mixture adjacent the discharge end of said passage to a temperature below the boiling point of the treating solution at atmospheric pressure and controlling the discharge from the passage. 110
7. The method of treating fibrous cellulosic material which includes forcing a mixture of fibrous cellulosic material and a treating solution comprising an aqueous solution containing about 0.5-2% sodium hydroxide by weight through a passage, heating the mixture within the passage to a temperature of about 165° C., cooling the mixture adjacent the discharge end of said passage to a temperature below the boiling point of the treating solution at atmospheric pressure and controlling the discharge from the passage. 120
8. The method of treating fibrous cellulosic material which includes forcing a mixture of fibrous cellulosic material and a treating solution through a passage, introducing steam into the passage to heat the mixture to a temperature substantially above the boiling point of the treating solution, cooling the mixture adjacent to the discharge end of the passage to a temperature below the boiling point of the treating solution at atmospheric pressure and controlling the discharge from the passage. 130
9. The method of treating cotton linters which includes forcing a mixture of cotton linters and a treating solution comprising an aqueous solution containing about 0.5-2% by weight of sodium hydroxide through a passage, introducing steam into the passage to effect heating of the mixture to a temperature higher than about 140° C., cooling the mixture adjacent the discharge end of the passage to a temperature below the boiling point of the treating solution at atmospheric pressure and controlling the discharge from the passage. 140
